CLAIM

We claim the ornamental design for a foot rest, as shown and described.

DESCRIPTION

FIG. 1 is a front perspective view of a foot rest, showing our new design;

FIG. 2 is a front view of a foot rest of FIG. 1;

FIG. 3 is a right side view of a foot rest of FIG. 1, the left side view is a mirror image of the right side view of FIG. 3;

FIG. 4 is a top view of a foot rest of FIG. 1; and,

FIG. 5 is a bottom view of a foot rest of FIG. 1.

1 Claim, 2 Drawing Sheets
